CLYDE P. MATTESON, OF DETROIT, MICHIGAN

FLAG

Application filed May 20, 1930. Serial No. 454,141.

This invention relates to means for preventing a substantially horizontally suspended flag or banner from becoming entangled about a supporting pole or halliard and has for its object the counteracting of the tendency of the fabric surface of the flag as a whole, combined with its flexible character to permit wind currents of constantly varying degrees and direction to create a belled or bagging effect in its central portion which tends to lift the flag from its normally dependent position not only to a more or less horizontal position but even so far beyond that as to permit the intermediate and end portions of the flag to drop upon or over the supporting staff when the wind current temporarily changes or when because of its attainment of a nearly vertical position the uplifting influence of the wind no longer has a lifting effect upon the bagged portion initially created, and also when the general angularity attained by the flag as a whole has reduced to a negligible degree any uplifting effect due to the presence in a greater or less degree of a vacuum tendency on the upper side of the flag.

It has been my experience that the mere weighting of the flag as for example by integrating a wooden or metal rod with the lower edge thereof as suspended merely accentuates the probability that the flag as suspended will lend itself to bending or flexing into a bagged or indent contour as the wind strikes it, thus, not only increasing the likelihood of the flag being raised by the wind to a point where its lower end will fall over upon and become entangled with the supporting staff or halliard but as well setting up an additional strain upon the fabric as such change contributes to the probability of its being torn or at least soiled by additionally frequent wiping of portions thereof against the supporting staff as the flag falls when the wind pressure temporarily ceases.

It being far from objectionable that such a suspended flag should be lifted by the wind from its initially vertically suspended position even to the degree of substantial coincidence with the horizontal or even slightly more, my study of the subject has led me to

the conclusion that the question of regulating its levitation in response to the wind currents to which it is subjected, and to the adoption of means for maintaining the flag against collapse upon and fall with the supporting staff may be compared more or less generally with the problems incurred in the designing of an airplane wing as regards its lengthwise cross-sectional contour. In other words, there is a certain point measured from front to rear of an airplane wing at which experimentation has found that the impinging wind pressure is the greatest and adjacent and immediately above the top surface of which there is a corresponding maximum of vacuum-induced lift; and applying this principle, subject to the modification that the flag fabric when drawn off tight represents a plane of uniform thickness rather than a contoured body of variant and tapered thickness, I apply the principles deducible therefrom to the application to the fabric or web of the flag as a whole and as suspended of locating at the corresponding point of maximum lift and uplifting air pressure a series of depressing weights which tend to counteract the bellng or concaving tendency of the flag at that point. This being done, such a proportion of the remainder of the flag surface as a whole namely that part relatively remote from the suspending staff or halliard cannot present or constitute such a potential bellng surface as will permit the end even when lifted by the wind to approach a location of tangible propensity to the staff so as to become fouled therewith.

In the drawings:

Figure 1 is an edge view of a flag in a horizontally blown position and of its supporting staff with the approximate and probable loci of unit lift at various points lengthwise of the flag indicated in dotted lines, or, in aeronautical or mathematical terms, its "forced polygon".

Figure 2 is a perspective of a horizontally suspended flag responding to the uplifting influence of a wind current but with an indication of the preferred positioning of the depressing weights hereinafter described at the points of maximum uplift.

Figure 3 is a similar perspective illustrating a horizontally suspended flag in ideally outblown position due to the cooperative action of the weights there shown.

5 Figure 4 is a detail sectional elevational view showing a preferred form of attaching means of a weight to the flag fabric.

10 Figures 5 and 6 are respectively elevational and edge views of a possible alternative method of attaching or structurally integrating the flag and the weights.

15 At A is shown a horizontally or nearly horizontally extending flag staff, such as would be supported upon the sill of a window particularly of an office or store building for effecting the displayed support of a flag over the sidewalk or street as a whole. Such flag may either be attached directly to the pole or may be carried upon halliards B. The 20 blanket or flag fabric as a whole is indicated at C, and of course may be of any desired dimensions and any relative size as regards contrasting length and width, and of such number of thicknesses of fabric as may be selected. It being desirable that the waving and undulation of the flag as a whole shall not result in its lifting and the swing of its free edge beyond the vertical line a—a shown in Figure 1, I find that in normal use the location 25 of maximum uplift of an undulated flag may generally be expected to be located at about the point outwardly from the suspended edge indicated by the dotted line b—b in Figure 1, and speaking in terms of proportionate 30 length, it is my experience that this point of maximum lift is located along the line approximately one-fourth of the distance from the staff-supported edge of the flag toward its outer or freely flapping end. Along this 35 line therefore I position a plurality of 40 weights as D, preferably in the form of flattened slugs positioned in pockets E which are inconspicuously and yet firmly sewed onto or between the layers of the main flag fabric, and 45 which by their presence in this point of maximum lift tend to break down or offset the wind-induced belling-up of the flag fabric at that point, thus maintaining the space as F located between that line and the supporting 50 staff or halliard relatively straight. For many purposes this is adequate to so space whatever belling-up may occur in the remaining and relatively remote three-quarters of the flag surface, so far from the supporting staff that even if such belling does occur on 55 that part, the fall thereof upon the temporary cessation of the wind current results only in its harmless and nonentangling fall upon the portion F nearest the staff, and in no event 60 permitting its passage beyond the line b—b such as would then permit its entanglement with the staff or halliard.

In such instances, if this provision does not prove adequate, I counteract the further or 65 supplemental belling-up of the flag as re-

gards the outer three-quarters of its wind exposed surface by the provision of preferably one additional weight, as G, only, this being located substantially centrally of the flag as measured from one lateral edge to another, thus locating this supplemental depressing weight at a point substantially central of the expected location of supplemental bulging or belling-up of the flag fabric. Thus, it will be noted that the location of the first pair of weights as D tend to keep stationary the entire width of the flag blanket nearest that supporting staff and in practically fully spread out position and the additional weight G tends to extend this influence through a large part of the remaining three-quarters of the surface of the flag thus leaving only the free outer corners as H free to flap and become temporarily pulled over onto the remaining portion of the flag blanket as a whole.

70 In some cases it may be advisable to further supplement this by the location of an additional air-foil-counteractive weight, as J, at a point intermediate the line to which the principal depressing weights D are located on the suspending staff or halliard, this being illustrated in Figure 3. In any and all of these forms however, it will be noted that the freely flying outer edge of the flag is subjected to no strain other than that of its own weight and that resultantly, any tendency to belling-up such as would result from the weighting of the entire free outer edge of the flag is fully avoided. Not only is this advisable from the standpoint of the 75 wind-induced belling-up, or bulging of the flag which would result from such an arrangement, but as well, any possibility of the breakage of windows in the floor beneath that from whose window the flag is suspended and in front of which the free outer edge of the flag would depend is avoided.

90 It will be obvious that in place of the pocket supports for the inclusion of the weights, as shown at D and E, the screw-integrated 95 weights M and N shown in Figures 5 and 6 could be easily substituted therefor without departure from the fair spirit of my invention, the screw K passing through a small 100 and if desired marginally reinforced hole in the flag fabric, and the two discs or weight members M and N closely pressed against the 105 surfaces of the flag fabric to a degree measured by their breadth or size, thus avoiding 110 to the maximum any tearing influence upon the fabric as the flag is flapped in the wind.

115 What I claim is:

1. Means for counteracting the tendency of a horizontally suspended flag to assume an 120 airfoil-induced contour, comprising a plurality of selectively positioned weight members 125 integratedly associated with the fabric thereof at the points of calculated maximum air lift upon its surface, whereby the belling-up 130

tendency of the fabric alone at those locations is weightedly opposed.

2. A display flag adapted for horizontal suspension from a support with which the avoidance of its possible entanglement due to air lift is desired, comprising a fabric blanket of selected dimensions and a plurality of weight members attached thereto at the points of expected maximum air lift.

10 3. A display flag, comprising a fabric base of suitable dimensions and a plurality of weight members associated with the body thereof at points of maximum air lift, whereby the tendency of the flag body to be lifted by the wind to a position of potential entanglement with a substantially horizontal supporting shaft is counteracted.

20 4. In combination with a pendently supported flag body, means for counteracting the tendency thereof to respond to the air lift influence of the wind, comprising a plurality of weight members attached thereto at approximately the expected location of the maximum airfoil pressure thereon.

25 5. In combination with a flag whose suspension along one edge from a substantially horizontal support is desired, a plurality of members responsive to gravity influence to a degree in excess of the interior portions of the flag's surface to which they are attached, adapted to counteract the tendency of the flag fabric as a whole to assume an air-foil induced contour upward.

35 6. The combination, with a pendently supported flag fabric, of weight members associated with those portions of the flag as a whole spacedly located from the marginal edges thereof, at which, the dimensions of the flag being taken into consideration, the maximum air lift may be expected to exert itself.

40 7. In combination with a pendently supported flag, a plurality of weight members attached to that portion of the flag's lengthwise extent at which the maximum air lift is reasonably expectable, whereby the wind-induced rise thereof to a position of possible entanglement with the element supporting the flag is opposed, while leaving the free end of the flag prohibitively far from possible lifting thereover and fall thereupon.

In testimony whereof I sign this specification.

CLYDE P. MATTESON.
